UNITED STATES PATENT OFFICE.

THOMAS P. GREGER, OF PHILADELPHIA, PENNSYLVANIA.

DESIGN FOR A MANHOLE-FRAME.

SPECIFICATION forming part of Design No. 29,313, dated September 6, 1898.

Application filed August 8, 1898. Serial No. 688,121. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design 5 for a Manhole-Frame, of which the following is a specification, reference being had to the accompanying drawings, forming part hereof, in which—

Figure 1 is a top or plan view of a manhole-frame of the shape or configuration of my design, and Fig. 2 is a vertical section through the frame on the line $x-x$ of Fig. 1.

15 The leading feature of my design consists of the unitary structure made the subject of illustration and having the shape or configuration shown and hereinafter described.

In the drawings, A represents the frame, 20 consisting of a tapering annular throat a , provided with an integral base b at an angle to

the frame a , and lugs c , with openings c' between them and extending entirely around the interior of said frame and forming a ledge C for the reception of a suitable cover, which is adapted to be inserted in the throat of said frame and so as to rest on the said ledge C . d and d' are semicircular recesses or grooves formed in one portion of the wall of the frame A, as illustrated in Fig. 1 of the drawings. 25 30

Having thus described my invention, what I claim as new, and desire to secure by Letters Patent, is—

The design for a manhole-frame, substantially as shown and described. 35

In testimony whereof I have hereunto set my signature in the presence of two subscribing witnesses.

THOMAS P. GREGER.
